LIFT TRUCK

William S. Foshee, Montgomery, Ala.

Application May 12, 1941, Serial No. 393,088

2 Claims. (Cl. 212—140)

This invention relates to a lift truck or dolly of that type adapted to straddle a load, pick it up, transport it from place to place, and set it down with a minimum of time and labor, and has for an object the provision of such a vehicle which shall be simple but extremely sturdy of construction whereby it is adapted to handle relatively heavy loads, together with improved power means for raising and lowering the load to be hauled.

A further object of this invention is to provide a vehicle of the character described which shall be constructed principally of standard steel shapes welded together, whereby it is easy of assembly, relatively light in weight, and capable of handling relatively heavy loads.

It is characteristic of lift trucks and dollies that they must straddle the load, and accordingly the frames thereof are necessarily open at one end and can not be cross braced except at the top and the front end thereof. The supporting wheels being on the outside of the frame, create a torsional strain on the frame, tending to spread it at the bottom. One of the distinctive features of my invention is found in the mounting of the axles of the vehicle in such a manner that they are inset with respect to the side frame members whereby to minimize this torsional spreading strain.

Another distinctive feature of my invention is found in the provision of a hydraulic cylinder with linkages connected thereto whereby the lifting means for the truck are all operated from a single power source.

Apparatus embodying features of my invention is illustrated in the accompanying drawings forming a part of this application, in which

Fig. 1 is a plan view of a lift truck constructed in accordance with my invention;

Fig. 2 is a side elevation of the same;

Fig. 3 is a perspective view illustrating the method of mounting the axles for the wheels of the truck;

Fig. 4 is a detail sectional view on an enlarged scale taken on the line IV—IV of Fig. 2;

Fig. 5 is a fragmental sectional view on an enlarged scale showing the linkages for raising the truck and looking in the direction of the arrows V—V in Fig. 2;

Fig. 6 is a view similar to Fig. 5, illustrating the construction of one of the vertical frame members with which the lifting means is associated;

Fig. 7 is a sectional view on an enlarged scale taken along the line VII—VII of Fig. 2; and

Fig. 8 is a piping diagram of the hydraulic

system employed in raising and lowering the lifting members.

Referring to the drawings, my improved lift truck is comprised of spaced vertically extending frame members 10, 11 and 12, the members 10 being at the rear of the vehicle, the members 12 toward the front of the load carrying portion of the vehicle, and the members 11 being intermediate the members 10 and 12 and carrying axles 14 upon which the wheels 16 are mounted.

As may be seen in Fig. 1, each of the vertical frame members is composed of two channels 17 and 18, joined together across the top by channels 19 and 21, which latter are preferably welded to the channels 17 and 18 whereby to form as sturdy a structure as possible.

The vertical frame members 10 and 11 are joined by a channel member 22, and the members 11 and 12 are joined by a channel member 23, the members 22 and 23 being welded to the individual channels 17 and 18, as shown in Fig. 3. A bottom brace channel 24 for the frame thus described extends from the member 10 to the member 12, being welded to both. The channel 24 lies beneath the members 17 and 18 which form the vertical frame member 11, as shown in Fig. 3. The vertical frame members 10 and 12 are further strengthened by means of relatively short plates 26, 27 and 28 welded to the outer faces of the channels 17 and 18. The vertical frame member 11 is strengthened by a continuous plate 29 welded to the outer flanges of the channels 17 and 18.

Secured to the inner flanges of the channels 17 and 18, preferably by welding, on both sides of the vehicle is a side wall 31, which is joined at the forward end of the vehicle to an end wall 32. The walls 31 and 32 may be joined together by means of angles 33 and 34 welded into the corners, as shown in Fig. 1. The side walls 31, being so joined to the vertical frame members, provide additional strength for the structure. The upper ends of the vertical frame members 10, 11 and 12 are joined by a continuous angle 36 welded to the inner faces of the channels 17 and 18.

Fitting within the side walls 31 is a movable inner wall 37 formed from a steel plate and having its lower edge resting on and secured to a relatively narrow plate 38. The plate 38 in turn is secured to and rests on lifting brackets 39 having upwardly extending arms 41 to which force is applied to raise and lower the load to be carried by the vehicle in a manner to be described later. The side walls 31 and 37 are flared at their rear ends, as shown at 42 and 43, to aid in

guiding the vehicle astride a load to be lifted. Also the lower plate 33 is bent downwardly at the rear, as shown at 44 in Fig. 2, for the same purpose.

Referring now to Figs. 3 and 4, I show in detail the manner of supporting the axles 14. As will be seen particularly in Fig. 3, the channels 17 and 18 embodied in the vertical frame member 11 are cut off short of the bottom of the side wall of the vehicle, and two angles 46 and 47 are rigidly secured thereto by welding. The angles 46 and 47 are also joined to the side wall 31 and to the lower channel 24. The butt of the axle 14 is then set in between the angles 46 and 47 and welded into plates 48 and 49, which latter are welded to the butt of the axle and to the angles 46 and 47, as shown in Fig. 4. By this means the supporting axles 14 are inset with respect to the frame members, and the torsional strain on the vehicle frame tending to spread it, is greatly reduced.

At the extreme upper ends of the vertical frame members 11 and 12, on one side, I secure a channel 51 upon which is mounted a hydraulic cylinder 52. The piston rod 53 associated with the cylinder extends rearwardly, as shown in Fig. 2, and is guided by a guide block 54 secured to the upper end of the vertical frame member 11. A crosshead 55 carried by the piston 53 has connected thereto links 57 and 58 which are connected at their other ends to the upper arm 59 of a bell crank which is rigidly secured to a shaft 61 mounted in a bearing 62, which bearing is supported on the angle 36, as shown in Fig. 6. The shaft 61 extends across the frame, as shown in Fig. 1, the other end being supported in a bearing 63 on the opposite side of the vehicle frame. A crank arm 64, similar to the lower arm 59 on the opposite side, is keyed to the shaft 61.

The arrangement of lifting means is identical on the two sides of the vehicle, and the description of one will be sufficient. The lower arm 66 of the bell crank extends through an opening 67 formed in the vertical channel member 17, and is joined to downwardly extending links 68 housed in the space between the channels 17 and 18. At the lower part of the frame, a bell crank having an upper arm 69 and a lower arm 71 is pivotally mounted on a pin 72, which is supported by a block 73 welded to a relatively short channel 74 which extends from the lower channel 24 to the upper channel 23 and is welded to both of said channels and to the side wall 31 of the vehicle. A brace 76 and a vertically extending plate 75 form an outer bearing for the pin 72, and the brace has one end secured at 77 to the vertical channel member 18. The lower arm 71 of the bell crank just described extends through an opening 78 in the channel member 18, as shown in Fig. 7, and is connected to the vertical links 68, already described. Also connected to the lower bell crank arm 71 is a short link 79 which is pivotally connected by means of a pin 81 to a guide block 82 slidably fitting between vertically extending guide members 85, which latter are welded to the channel members 17 and 18, as shown in Fig. 7. The guide block 82 is secured to the vertical arm 41 of the bracket 39, whereby, upon movement of the bell crank, vertical motion is imparted to the lifting brackets 39.

The lower arm 69 of the lower bell crank just described is connected by means of links 83 which extend rearwardly through suitable openings 84

in the channel members 17 and 18, as shown in Fig. 6, being joined at the rear of the vehicle to the upper arm 86 of a similar bell crank which has a lower arm 87 connected to short links 79a to a guide block 82a which is connected to the vertical arm 41 of the rear lifting bracket 39. The bell crank just described is mounted similarly to the forward bell crank on a bearing pin 88, in channel and plate members similar to 14 and 75, supported between the channels 22 and 24, and by means of a brace 91 similar to the brace 76.

From the foregoing description of the lifting means it will be seen that when the piston rod 53 of the hydraulic cylinder 52 moves rearwardly out of the cylinder 52, the lifting brackets 39 are raised, thus lifting any load resting on the lifting brackets 39. When the piston rod 53 moves inwardly of the cylinder 52, the lifting brackets 39 are lowered, thus depositing any load which may be carried by the vehicle.

It will be understood that my improved lift truck is intended to be hauled by a power means, not shown, connected to a draw bar 92 at the forward end of the vehicle. It is also contemplated that power may be supplied from the vehicle through a flexible shaft 93. It is from this power takeoff shaft 93 that I contemplate developing the pressure necessary to supply the hydraulic cylinder 52. The piping arrangement is best understood by reference to the diagrammatic Figure 8. The shaft 93 is connected to a rotary pump 94 which draws a suitable fluid from a storage reservoir 96 mounted on the front of the vehicle. The fluid under pressure from the pump 94 is delivered through a conduit 97 to a three-way valve 98. From the valve 98, the fluid may be discharged through a conduit 99 to the cylinder 52, or released therefrom to flow back through the valve to the reservoir 96. A pressure relief valve 101 prevents damage to the apparatus due to building up too high pressure. A drain conduit 102 permits any fluid leaking past the piston of the cylinder 52 to drain to the reservoir 96.

From the foregoing the operation of my improved lift truck will be readily understood. The truck is backed astride a load to be carried with the lifting brackets 39 in position to engage the load. With the pump 94 in operation, the valve 98 is turned to connect the delivery conduit 97 with the conduit 99 leading to the cylinder 52, whereupon the piston rod 53 moves outwardly, rocking the bell crank arms 59 and 66, and thence through the links 79, and the bell cranks 69 and 86, exerting a lifting movement on the lifting brackets 39 and raising the load. The load may be held in its elevated position simply by moving the valve 98 to the position shown in Fig. 8, with all the ports blanked off. For long distance hauling, it may be desirable to interpose some mechanical means, not shown, to sustain the load, many such means being known in the art. Whenever it is desired to lower the load, the valve 98 is turned to connect the conduit 99 with the reservoir 96, thus releasing the pressure in the cylinder 52.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. In a lift truck of the character described, a frame comprising a plurality of pairs of vertically disposed channels spaced to form front, intermediate and rear side frame members, transverse beams interposed between and secured to the upper ends of each pair of vertical channels, upper, intermediate and lower longitudinally extending beams interposed between and secured to the side frame members, an axle for a supporting wheel secured to the lower end of each of the intermediate side frame members, a side wall and a forward end wall for the truck body secured to the side frame members, vertically movable lift members extending below the side wall, and guide means for the lift members between the channels forming the pairs of vertical side frame members.

2. In a lift truck of the character described, spaced front, intermediate and rear vertical 20

frame members each comprised of a pair of channels the opposed pairs being joined at the top by cross channels secured thereto, vertical plates joining the adjacent webs of the pairs of channels on the outside thereof, side walls joined to the inward sides of the vertical frame members, longitudinal braces joining the vertical frame members intermediate their ends and near the bottom thereof, lift members comprising brackets extending inwardly beneath the side walls and adapted for vertical movement, vertical arms for the brackets extending upwardly between the vertical channels, guides secured to the channels for the vertical arms, a source of hydraulic pressure, a cylinder and piston therein, linkage means connecting the piston to the lift members to raise and lower the latter, and a valve for controlling the flow of hydraulic pressure to and from the cylinder.

WILLIAM S. FOSHEE.
